United States Patent

Des. 240,559
Patented July 13, 1976

240,559

PERITONEAL DIALYSIS UNIT OR THE LIKE

Harold H. Kawaguchi, Seattle, Wash., assignor to
Physio-Control Corporation

Filed July 11, 1974, Ser. No. 487,469

Term of patent 14 years

Int. Cl. D24—01

U.S. Cl. D83—1 F

Fig. 1

Fig. 2

Fig. 4

Fig. 5

FIG. 1 is a front perspective view of a peritoneal dialysis unit or the like showing my new design;

FIG. 2 is a rear perspective view thereof;

FIG. 3 is a left side elevational view thereof;

FIG. 4 is a top plan view thereof; and

FIG. 5 is a right side elevational view thereof.

I claim:

The ornamental design for a peritoneal dialysis unit or the like, as shown.
